UNITED STATES PATENT OFFICE.

JOHN B. SALO, OF BYESVILLE, OHIO.

NAIL-PULLER.

SPECIFICATION forming part of Letters Patent No. 686,540, dated November 12, 1901.

Application filed April 9, 1901. Serial No. 55,021. (No model.)

To all whom it may concern:

Be it known that I, JOHN B. SALO, a citizen of the United States, and a resident of Byesville, in the county of Guernsey and State of Ohio, have invented a new and Improved Nail-Puller, of which the following is a full, clear, and exact description.

This invention relates to improvements in nail-pullers; and the object is to provide a nail-puller of simple construction that may be readily engaged with a fastening-nail of a box or the like and then by a continuous rotary motion draw out the nail.

I will describe a nail-puller embodying my invention and then point out the novel features in the appended claims.

Reference is to be had to the accompanying drawings, forming a part of this specification, in which similar characters of reference indicate corresponding parts in all the figures.

Figure 1 is a side view, partly in section, of a nail-puller embodying my invention. Fig. 2 is a front view, and Fig. 3 is a bottom view, of the same.

Referring to the drawings, 1 designates a frame, from which a leg 2 extends downward to be engaged with a box or other device from which a nail is to be drawn. Mounted to slide and to have vertical movement in bearings 3 on the frame is a draw-rod 4, and to permit of the upward movement of this draw-rod a handle 5, which is connected to the frame 1, is made tubular, as clearly indicated in Fig. 1.

Mounted on a shaft 6, which has a bearing 35 in the frame 1, is a bevel-gear 7, meshing with a bevel-pinion 8, mounted on the draw-rod 4. This pinion 8 is designed to impart a rotary motion to the draw-rod; but the draw-rod is movable vertically through the pinion. For 40 this purpose the draw-rod is provided with a slot 9, into which a feather on the inner side of the pinion may pass. From a wrist-pin 10 on the bevel-gear 7 a link 11 extends to a connection with a lug 12, attached to the draw-rod.

Attached to the lower end of the draw-rod is a shell 13, and pivoted on a cross-bar 14 in said shell are jaws 15 and 16. The upper ends of these jaws have link connections 17 and 18 with the lower end of the draw-rod.

The jaws 15 and 16 extend downward substantially to a point, and the inner surfaces are

corrugated, as at 19, so as to firmly grasp the head of a nail. On the outer surfaces the jaws have threaded portions 20, designed to cause the jaws to feed into the wood, and said outer surfaces also have auger-like cutting edges 21. It will be noted that the teeth on the gear 7 extend only partially around the same or form a segment of a circle.

In operation to draw a nail the jaws when slightly separated are engaged with the wood at opposite sides of the nail-head and with the leg 2, resting on the wood or box, and upon rotating the shaft 6 by means of the crank 22 thereon the segmental gear will rotate the pinion 8, consequently rotating the jaws, which will feed downward into the wood. Then after the teeth of the segmental gear shall have become released from the pinion and the rotary movement of the gear 7 is continued the link 11 will cause the draw-rod to move upward, and the links 17 and 18 by being drawn upward will cause the jaws to engage tightly with the head of the nail, so that said nail will be drawn out as the rod moves upward.

Having thus described my invention, I claim as new and desire to secure by Letters Patent—

1. A nail-puller, comprising a frame, a leg 80 on said frame, a rod movable vertically in the frame, jaws on the lower end of said rod for engaging with the nail-head, a wheel mounted in the frame and having a segmental row of gear-teeth, a pinion on the rod with which 85 said gear-teeth are designed to engage, the rod being adapted to slide through the pinion but to rotate therewith, and a link connection between the wheel and the rod, substantially as specified.

2. A nail-puller, comprising a frame, a leg 90 extended downward from said frame, a draw-rod movable vertically and having a rotary movement in the frame, pivoted jaws at the lower end of said rod, link connections between the upper ends of the jaws and the rod, a bevel-pinion mounted on the rod and through which said rod may slide, a segmental bevel-gear for engaging with said pinion, and a link connection between the segmental 95 bevel-gear and the rod, substantially as specified.

3. In a nail-puller, a frame, a leg extended downward from the frame, a rod having slid-

ing movement in the frame and also adapted to rotate therewith, means for imparting the rotary motion to said rod and also a longitudinal motion, pivoted jaws at the lower end 5 of said rod and having link connection therewith, said jaws being extended substantially to a point and threaded, and cutting edges on said jaws, substantially as specified.

4. In a nail-puller, a frame, a draw-rod, jaws 10 at the lower end of said rod, and means for

imparting rotary and vertical movement to the draw-rod, substantially as specified.

In testimony whereof I have signed my name to this specification in the presence of two subscribing witnesses.

JOHN B. SALO.
